UNITED STATES PATENT OFFICE.

JOSEPH KRELL, OF BERLIN-PANKOW, GERMANY, ASSIGNOR TO THE FIRM ADREMA
MASCHINENBAUGES M. B. H., OF BERLIN, GERMANY.

PRINTING PLATE AND THE LIKE.

Application filed March 9, 1925, Serial No. 14,242, and in Germany June 20, 1924.

This invention relates to printing plates for addressing machines of the kind in which the printing plates are moved through the machine in their longitudinal direction one after the other in guides with which guiding edges provided on the upper and lower margins of the printing plates coact. Such printing plates have hitherto always been so constructed that their two guiding edges are completely symmetrical with one another. Now when such printing plates are employed the disadvantage frequently arises that owing to the printing plates being exactly symmetrical in profile, some or all of them may be inserted in the machine wrongly and run through the machine upside down, their rear guiding edges moving along the front guides of the machine. This has the result that the printed addresses are upside down, which for the sorting of the envelopes of wrappers is very undesirable. It is also very troublesome if when storing the printing plate away in collecting boxes it is found that some of the printing plates are upside down so that they have first to be turned over.

With a view of avoiding these difficulties the invention according to this invention is particularly distinguished by the fact that the two guiding edges or marginal guides of the printing plates are differently shaped, so that the printing plates can only pass through the addressing machine in a certain fixed position in which the front and rear guides for the printing plates are correspondingly differently shaped. The different configuration of the two guide edges may be accomplished in various ways. In a preferred form of construction according to this invention the ordinary printing plates in which the guiding edges possess two overlappingly or overlyingly folded strips of sheet metal these guiding means are disposed at different levels relatively to the printing surface of the printing plate, while otherwise the guiding edges are of the same construction. Printing plates of this kind can be easily manufactured, and on the other hand, a very slight modification of the addressing machines, as heretofore constructed, is sufficient to adapt the same to the working with the new printing plates.

In accordance with this invention not only single printing plates with no incision or with but one incision or recess at one of the

guiding edges, usually the upper guiding edge, may be modified in accordance with the principles of the invention, but also printing plates with a plurality of incisions or recesses in one or both guiding edges, and the invention may also be applied to longitudinally subdivided printing plates and provided with a portion to be inserted into the flanges of the guiding edges.

The invention will be more fully described with reference to the accompanying drawing, showing by way of example various embodiments of the invention, Figure 1 and Figure 2 showing a preferred construction in elevation and respectively in section on the line II-II of Figure 1. Another modification is shown in Figures 3 and 4, and Figures 5 and 6 show a third modification. Figure 7 is a cross section through the printing plate of Figure 2 on an enlarged scale.

Figure 1 shows in front elevation a printing plate *a* for an addressing machine, made, for instance, of zinc, with a recess *b* in the upper guide edge. The two guiding edges *c* and *d* consist of two doubled up layers of sheet metal folded closely upon each other, as appears from Figures 2 and 7. The guiding edge *d* is at a somewhat higher level with relation to the base of the printing plate than the upper guiding edge, as indicated at *e*. In view of the fact that in accordance therewith in the addressing machine for which the printing plates shown in Figures 1 and 2 are intended the front guide is somewhat higher than the rear guide, the printing plates shown will always pass through the machine in the right direction only.

In the form of construction according to Figures 3 and 4 in which Figure 3 is a rear elevation of the printing plate, the same is provided with several recesses *b'* in the upper guide edge *c'* of the plate *a'*; moreover, in the modification the lower guiding edge *d'* is not at a higher level than the upper guiding edge *c'*; but the latter edge *c'* is at a higher level for the amount of the distance *e'* than the lower guiding edge *d'*.

In Figures 5 and 6 is illustrated a printing plate *a''* which is subdivided transversely to its longitudinal direction and has an exchangeable part *f* slidable into the folds of the upper guiding edge *c''* and lower guiding edge *d''*. In the case of this con-

structural form the guiding edges c'' and d'' are constructed at the same altitude relatively to the printing surface and of the same thickness but of different breadths, as shown more particularly in Figures 6, if the breadth measurements g and h of the guiding edges c'' and d'' are compared with one another.

We are aware that it has previously been proposed to provide the printing plates of addressing machines with ribs along their longitudinal edges for the purpose of strengthening these edges and spacing the plates apart when stacked and we wish it to be understood that we do not claim such a construction.

I claim:—

A printing plate for addressing machines, wherein the printing plates are moved in succession in their longitudinal direction through the addressing machine and guides and wherein each plate includes a body, guiding members provided on the upper and lower marginal edges of the body of each plate for coacting with the guides and are arranged at different heights and in relation to the printing surface on the body of the printing plate, so that the printing plates can only pass through the addressing machine in one definite position.

In testimony whereof I affix my signature.
JOSEPH KRELL.
